UNITED STATES PATENT OFFICE.

JACOB BLOCK, OF CINCINNATI, OHIO.

IMPROVEMENT IN FIRE-EXTINGUISHERS.

Specification forming part of Letters Patent No. 178,101, dated May 30, 1876; application filed April 6, 1876.

To all whom it may concern:

Be it known that I, JACOB BLOCK, of Cincinnati, Hamilton county, Ohio, have invented certain new and useful Improvements in Fire-Extinguishers, of which the following is a specification:

My invention consists in constructing fire-extinguishers in such a manner as to effectually prevent either the acid or alkaline solutions becoming mixed with the water in the generator, except at the very moment when the apparatus is to be used, at which time these two chemical agents are caused to combine by the simple act of depressing a rod, or its equivalent appliance, whose upper end projects through the cap of the machine. This generator or water-tank has located within it two distinct and detachable chambers, receptacles, or vessels, of which the upper receptacle is an inverted acid-bottle, depending from the under side of the cap of the machine, and having at its lower end a cork, stopper, or plug, that is withdrawn when the previously-described rod is forcibly depressed. Simultaneously with this withdrawal of the stopper a stem at the lower extremity of the operating rod or shaft impinges against a downwardly-opening valve, applied to the upper end of the other internal receptacle or chamber, which latter contains the alkaline solution. The contact of this stem opens said valve, and thereby permits the descending charge of acid to flow directly into the now open mouth of the alkali-chamber. This direct mixture of the highly-concentrated acid and alkali causes a violent effervescence to take place within the generator, and the result is, that the entire fluid contents of the latter are immediately set in circulation, which circulation opens upwardly a trap or valve at the bottom of the alkali-chamber, thus effecting the most thorough impregnation of the water with the two chemical agents, as hereinafter more fully described.

In the annexed drawings, Figure 1 is a representation of my improved fire-extinguisher, the generator being shown in section and uncharged, while the acid and alkali receptacles are in elevation. Fig. 2 is an axial section through the apparatus, the generator being shown charged with water and the plunger

depressed, so as to precipitate the acid into the alkali. Fig. 3 is a section through a portion of the cap, the latter being detached from the apparatus and inverted for the purpose of charging the acid-bottle; and Fig. 4 is an axial section through the alkali-receptacle detached from the extinguisher.

The principal member of my apparatus consists of a tank or generator, A, of any suitable size, and stout enough to resist the pressure that such vessels are usually subjected to. This tank is provided with two heads, B and C, of which the lower one, B, is imperforate, while the upper one, C, is furnished with a neck, D, to receive a cap, E. This cap is screw-threaded interiorly at F, to engage with the external or male screw of the aforesaid neck. Secured either to the upper or under side of this cap is a stuffing-box, G, traversed by a rod, shaft, or plunger, H, whose upper end carries a knob, button, or handle, I. Said rod H is slotted at J, to receive a key, wedge, or other retaining device, K, which latter is capable of being readily disengaged from the slot whenever it is desired to depress shaft H; but, if preferred, a screw or other appliance may be employed for operating the plunger. The lower end of this rod is bent horizontally at L, and supports a suitable plug, bung, cork, or stopper, M, of bottle N, said bottle being secured to the under side of cap E with spring-clips O, or otherwise, so as to permit said bottle being readily detached when it is to be filled with acid.

Projecting downwardly from arm L is a short stem, P, which occupies an axial, or nearly axial, position within the generator, said stem being adapted, when depressed, to impinge against the exposed surface of a valve or lid, Q, that closes the mouth R of alkali-chamber S. This lid is maintained in its normal or closed condition by an internal spring, T, or its equivalent device. The alkali-chamber S is a tube or vessel of any appropriate size and shape, and it is preserved in its proper position within the generator by a spring-holder, U, or otherwise. Said vessel is provided near its lower end with a perforated head, V, whose opening is covered with an upwardly-swinging valve, W, any suitable kind of gasket being interposed between

valve or flap and its seat V. X is the discharge-pipe, having a controlling cock or faucet, Y, and a screw-threaded coupling, to which latter the hose is attached in the usual manner. Z are notches or channels at the lower end of tube S, to allow a free entrance of water at the bottom of said tube when its flap W is opened.

My extinguisher is charged and operated in the following manner: The cap E is first unscrewed from neck D, so as to permit withdrawal of tube S, which tube is then filled almost full with any suitable alkaline solution, after which said receptacle S is restored to its original position within the spring holder or clamp U. Cap E is then inverted, and shaft H forced upwardly and turned, so as to withdraw stopper M and swing the latter to one side of bottle N, as seen in Fig. 3. This act leaves the bottle in such a condition as to be readily filled with any suitable acid; and as soon as this has been accomplished the cork is again inserted in the neck of the bottle, and secured therein by inserting key K in the slot J. The tank A B is now filled with water, but not so high as to overflow the mouth of tube S, as it is desired to keep the contents of these two vessels separate until the extinguisher is to be used. The tank being thus charged, the cap is screwed down upon neck D, and the apparatus is at once ready for use.

It will be apparent that in this normal position of the machine there can be no possibility of the contents of receptacles A, N, and S being accidentally brought in contact with each other, because stopper M prevents escape of acid from bottle N, while the pressure of alkaline solution upon flap W excludes water from tube S. As soon, however, as the machine is to be used for extinguishing a fire, the contents of these three receptacles are caused to mingle together by the simple act of depressing plunger-rod H, which can be done with the greatest facility after key K has been withdrawn from slot J. The moment this rod is depressed stopper M is withdrawn, and simultaneously therewith stem P opens valve Q, and discharges the entire contents of acid-receptacle N directly into the now open upper end or mouth of tube S.

The strong acid, being precipitated bodily into the highly-concentrated alkaline solution, produces an active effervescence, the contents of tube S boiling over at the mouth R, and escaping down into the water in tank A. This instantaneous and intimate mixture of acid, alkali, and water produces a violent commotion in tank A, the currents produced by this circulation being sufficient to open flap W, as indicated by arrows in Fig. 2.

The above-described circulation continues until the entire contents of the extinguisher are forced out through discharge-pipe X, in the usual manner, the cock Y having been previously opened.

One great advantage peculiar to my appa-

ratus is, that no mixture of the acid or alkali with the water takes place until the very moment when the extinguisher is brought into action, and, therefore, the sheet-metal tank A does not become corroded by the chemicals employed. This complete isolation of the acid and alkali within their respective vessels enables me to employ the most highly concentrated chemicals known to the art, and, consequently, the action of the extinguisher will be correspondingly prompt and energetic.

I am aware that extinguishers have been constructed with separate chambers for acid, alkali, and water; but such receptacles have always been external to the tank A, and connected therewith by a complicated system of pipes and cocks. This construction produces a very heavy, unwieldy, and expensive apparatus, as all of these vessels must be strong enough to stand the same pressure that tank A is subjected to. My arrangement does not increase either the size or weight of the extinguisher, because the two receptacles N and S are internal ones, and being subjected to the same pressure, both on their outsides and insides, they may be made of very light and thin metal or other materials.

I am also aware that it is not new to apply a glass acid-vessel to the cap or lid of an extinguisher, as several machines with such attachments are now in use; but in most of these the bottle is broken and destroyed when the apparatus is brought into action. This defective construction renders such machines unfit for use in the country, or in any other locality where it is difficult to procure a new acid-receptacle after the original one has been broken. On the contrary, with my apparatus the bottle is never injured, and, therefore, a single acid-receptacle will last for an indefinite period of time, and as said bottle is capable of being readily detached from the cap it can be carried in the pocket to a drug-store and refilled at a trifling cost.

As the gist of my invention consists in providing separate vessels for the acid and alkali within the generator, and causing the contents of these three receptacles to combine only when the apparatus is to be used, it is evident the construction of the acid and alkali chambers, and also the appliances for setting the extinguisher in operation, may be varied to suit circumstances. In some cases it may be desirable to fix the vessels N and S securely within the tank, and to carry the operating-shaft H, or its equivalent device, either down through the bottom of the tank, or else out at the side of the same.

I claim as my invention—

1. A fire-extinguisher whose generator or tank A has the acid-vessel N and the alkali-vessel S located within it, said tank being provided with a plunger, H, or other device wherewith an external force may be applied to cause the contents of said receptacles N and

S to combine with the fluid in the generator proper, substantially as herein described and set forth.

2. In combination with tank A and its internal receptacles N and S, the plunger H, or its equivalent, for simultaneously opening the delivery end of receptacle N and the receiving end of receptacle S, substantially as described, and for the purpose stated.

3. The internal alkali-chamber S, when provided with the oppositely-opening valves or flaps Q and W, as and for the purpose stated.

4. In combination with the internal acid-vessel N and alkali-chamber S, the plunger H J K L M, as and for the object stated.

5. The detachable and inverted acid-chamber N, secured to the under side of cap E with spring-clips O, or their equivalents, for the purpose set forth.

6. The combination of tank A B C D, cap E, plunger H J K L M, removable acid-bottle N O, and detachable alkali-receptacle Q R S V W, as herein described and set forth.

In testimony of which invention I hereunto set my hand.

JACOB BLOCK.
